Des. 179,749
Patented Feb. 19, 1957

179,749

CHAISE LOUNGE

George M. Wenzel, San Francisco, Calif.
Application April 4, 1956, Serial No. 40,909

Term of patent 14 years

(Cl. D15—11)

FIG. 1

Des. 179,749

PAGE 2

FIG. 2

Figure 1 is a perspective view of a chaise lounge; Figure 2 is a top plan view of said chaise lounge; and Figure 3 is a bottom perspective view of said chaise lounge.

The dominant features of the design reside in the portions shown in full lines in the drawings.

I claim:

The ornamental design for a chaise lounge, as shown and described.
